UNITED STATES PATENT OFFICE.

GEORGE J. DEHN, OF CHICAGO, ILLINOIS.

DRAIN.

1,139,647.

Specification of Letters Patent. Patented May 18, 1915.

Application filed March 28, 1910. Serial No. 552,000.

To all whom it may concern:

Be it known that I, GEORGE J. DEHN, a resident of Chicago, in the county of Cook and State of Illinois, have invented certain new and useful Improvements in Drains, of which the following is a full, clear, and exact description.

The invention relates to drain-traps and pipes for conducting drainage from a floor 10 or basin to the sewer.

In installing drain-pipes and traps, it is endeavored to lay the sewer-pipes beneath the floor such distance as will cause the drain-receiver to be properly disposed with 15 respect to the floor and so that the receiver may be connected to the sewer-pipe by a fitting of predetermined size. In practice, however, it frequently occurs that the floor is not always laid at the particular elevation 20 it is intended to be, or that the floor when laid and the sewer-pipe are not in correct relation to permit the drain-receiver and trap to be connected to the sewer by the fitting which was intended to be used, and 25 this difficulty frequently results in the necessity of re-laying a portion of the sewer-pipe or in imperfect drainage resulting from improper disposition of the drain-receiver. In some instances, a fitting of another size 30 must be provided and in others special fittings become necessary to overcome this difficulty. The present invention designs to overcome this difficulty by providing an adjustable connection in the trap-pipe which 35 permits the drain-receiver to be accurately set in correct position relatively to the floor and the discharge terminal of the trap-pipe to be properly connected to the sewer pipe, despite any variation in the relative position 40 of the sewer-pipe and the floor which frequently occurs in practice.

In practice, it has been found that in drain-traps having a liquid-seal therein for preventing gas from escaping from the 45 sewer, when the system is out of use for a long time, the liquid evaporates and the trap is rendered ineffective to prevent escape of gas from the sewer, and the invention also designs to provide an improved 50 drain-trap which comprises a valve in the receiver-basin, which can be manipulated to close the trap-pipe and prevent gases from escaping from the sewer when the liquid-seal is inoperative.

The invention further designs to provide

a drain trap and pipe of improved construction.

The invention consists in the several novel features hereinafter set forth and more particularly defined by claim at the conclusion 60 hereof.

In the drawings: Figure 1 is a central section of an improved drain trap and receiver embodying the invention. Fig. 2 is a horizontal section on line 2—2 of Fig. 1. 65 Fig. 3 is a section on line 3—3 of Fig. 1. Fig. 4 is a perspective of the ring for closing the upper end of the drain-pipe, and to which the seat and cage for the back-water valve are secured. Fig. 5 is a perspective of 70 a cage for the back-water valve. Fig. 6 is a section on line 6—6 of Fig. 1. Fig. 7 is a detail section on an enlarged scale of the seat for the back-water valve.

The improved drain-pipe comprises a section 11 having an upwardly extending drain-receiving terminal and a section 12 having a trap-bend 13 therein and a laterally extending discharge-terminal 14, which is adapted to be connected to a sewer-pipe. 75 The liquid in the trap-bend forms a seal for preventing gases from escaping from the sewer through the drain-receiving terminal of the drain-pipe. A suitable connection 15 extends upwardly from the laterally extending discharge-terminal 14 and is adapted to receive a vent-pipe, as well understood in the art. The upwardly extending portion of section 12 of the drain-pipe is slightly 80 enlarged, as at 16, to receive the lower end 85 of pipe-section 11, so that one section of the pipe will telescope into the other and permit pipe-section 12 to be connected to the sewer-pipe and the section 11 which carries the drain-receiver B, to be set in 90 correct relation to the floor. That is, if the floor has been laid in any other than the 95 exact relation with respect to the sewer-pipe for a connection or fitting of a certain size, the drain-pipe may be extended or shortened 100 by reason of the telescopic connection between the pipe-sections 11 and 12, to adapt the fitting for making a proper connection between the sewer-pipe and the receiver, leaving the latter properly disposed with 105 respect to the floor, despite inaccuracies or variations in laying the sewer-pipe and floor. The upper end of pipe-section 12 is provided with lugs or a flange 17 to receive bolts 18 which are adapted to extend 110

through a collar 19 which is adapted to jam a packing ring or gasket 20, usually of elastic material such as rubber, against the inner pipe and to form a water-tight connection between the telescopically connected pipe-sections when they have been adjusted into the desired relative position. Thus, it will be seen that the drain-pipe is readily adaptable for use in buildings in which the sewer-pipe is laid different distances below the floor or other structure from which the drainage is to be conducted to the sewer-pipe. The device is, therefore, rendered adjustable and the necessity of manufacturing different fittings according to the different distances between the floor and the sewer-pipe, is avoided. In order to increase the range of adjustment, pipe-section 11 is formed with annular grooves 21 which facilitate the cutting of the pipe by suitable tools, so that it may be shortened to the desired length when an unusually short vertical section is desired.

The upwardly extending inlet-terminal of pipe-section 11 is provided with an integral annulus a^4 adapted to form a seat for the base b of a drain-receiver B. The outer wall b' of the receiver is flared upwardly from its base-rim to form a receiving basin 30 and is provided with a top-flange or rim b^2 . An annular recess or shoulder b^3 is formed in the receiver to retain a perforated strainer-cover C, which is usually disposed, so it will be flush with the top of the basin 35 and removably held therein to provide access to the basin and the parts therein. The receiver-basin B is secured on the pipe-flange a^4 by any suitable means, for example: the interlocking slip and wedge connection shown in Letters Patent of the United States, No. 935,000, granted to me September 28, 1909. At each side, the receiver is provided with a suitable connection b^7 adapted for connection to a drain-pipe, when it is desired to discharge drainage from a basin or other receptacle into the drain-receiver B. By providing a connection b^7 at each side of the receiver, a connection may be made at each side and if but 50 one connection or neither of the connections is to be used, they can be closed by a plug b^8 .

A strainer D is removably sustained on a shoulder d in the receiver, some distance below the top C and the purpose of the internal strainer D is to catch matches or material likely to obstruct the passages in the drain pipe or the back water valve. In practice, it frequently occurs that in order to dispose of matter which will not pass 55 through the strainer-top C, the latter will be removed and this matter will be swept into the drain-receiver. In that event, the strainer D will catch such matter and prevent the back-water valve and the trap from becoming clogged thereby. The strainer D

can be occasionally cleaned to prevent the device from becoming clogged.

The inlet-terminal or upper end of section 11 of the trap-pipe has removably secured thereto, by screws b^5 , a ring E which is 70 usually made of brass. An elastic ring F, usually formed of rubber, is secured to the bottom of ring E, by screws e. A spherical float-valve G is adapted to be raised by liquid under back-pressure in the trap-pipe, 75 which will cause the float-valve to rise and engage the elastic seat and form a water-tight closure, to prevent any liquid from being forced backwardly through the inlet terminal of the drain-pipe. 80

In practice, it has been found that sometimes the water from the sewer is caused to gurgle which results in fluttering the float valve, so that the latter will not effectively prevent the back flow of the water through 85 the inlet terminal of the drain-pipe. By providing an elastic seat-ring, the float-valve adheres to the seat during this gurgling action and effectively prevents back-flow of the water, and furthermore the elastic seat-ring and ball form an effective closure against back-pressure of water in the drain-pipe. The upper end of pipe-section 11 is enlarged, as at 11^a, to receive a cage H for guiding the float-valve G. This 95 cage comprises a ring h' having inwardly extending wedge lugs h^2 which are adapted to pass through notches e^2 between outwardly extending wedge-lugs e' on the bottom of ring E, and by slipping ring h' on 100 ring E and then turning said ring relatively to ring E, said lugs may be brought into position to wedge and interlock and to removably secure the cage in position to guide the float valve. Guide-bars h are secured to the ring h' and the bottom portions of these bars serve to limit the downward movement of the float-valve, so that it will not be displaced by water rushing downwardly 110 through the inlet-terminal of the trap-pipe. 110

The inlet-terminal of section 11 of the trap-pipe extends above the base of the receiver B to collect sediment in the receiver-basin and causes the lower portion of the receiver to remain filled with water, which tends to lower the temperature of, and prevent undue evaporation of the water in the drain-pipe. In practice, it has been found, however, that in some instances, where the drain-pipe is seldom or infrequently used to carry off drainage, the liquid in the seal does evaporate, so that gases from the sewer will pass up through the drain-receiver. To prevent this from occurring, the inlet-terminal of the drain-pipe is provided with a register-valve which, when closed, will prevent gas from passing to the receiver from the sewer. This register-valve I comprises a perforated annular vertically extending wall i provided with lugs i' through which 120 125 130

screws δ^5 pass, which secure the ring E on the drain-pipe and also secure the body of the register-valve thereon. A top wall i^3 is formed on the side-wall i . A rotary valve-
5 member has a cylindrical side-wall i^4 fitting against the inner face of perforated wall i and has perforations corresponding to those in said wall i , so that when the openings in both walls are in registry, drainage can pass
10 therethrough into the upper end of the drain-pipe. The rotatable member of this valve is provided with a stem i^5 which projects through top-wall i^3 , and has secured thereto an arm or handle i^6 whereby the
15 valve may be opened or closed. Stops i^7 are provided to limit the play of the valve. The rotatable valve-member is confined vertically between the ring E and the top-wall i^3 of the valve-body. When, therefore, the
20 drain is to remain out of use for a long time, or if the back-water valve should become inoperative, the valve I may be closed and the escape of gas or water from the sewer, when the liquid seal has become in-
25 operative, will be obviated.

The form of valve set forth provides a structure in which the openings leading to the passage in the drain-pipe extend vertically, while the top is closed, and resultantly, 30 solid matter passing through strainer D will be directed to the bottom of the basin, and kept out of the drain-pipe, thus preventing the latter from becoming clogged. This feature is an important one if the in-
35 ternal strainer D is not employed, or if through over-sight it is not placed in the basin. The central or that portion of this strainer, which is disposed above the inlet-terminal of the drain-pipe, is imperforate
40 and only perforated around its outer edge to direct the drainage to the outer portion of the basin so the sediment will be retained in the basin, and the liquid will pass through the vertically extending openings in the reg-
45 ister-valve. When the register-valve is not employed, the internal strainer with its imperforate central portion prevents soild matter from being deposited into the inlet-terminal of the drain-pipe, and when the regis-
50 ter-valve is employed, the accumulation of matter on the top of the valve, is prevented.

The invention is not to be understood as restricted to the details shown and described,

since these may be modified within the scope of the appended claims without departing 55 from the spirit and scope of the invention.

Having thus described the.invention, what I claim as new and desire to secure by Letters Patent, is:

1. In a drain, the combination of a re- 60 ceiver-basin, a drain-pipe connected to receive drainage from said basin, a water-trap, a back-water valve, an upwardly extending register valve secured at the upper end of the inlet-terminal of the drain-pipe for pre- 65 venting escape of the gas through the drain-pipe when the water trap is inoperative.

2. In a drain, the combination of a re- 70 ceiver-basin, a drain-pipe connected to receive drainage from said basin, a water-trap, 70 a back-water valve, and a register-valve comprising a body secured at the upper end of the inlet-terminal of the drain-pipe, and having an upwardly extending perforated annular wall and a correspondingly perfo- 75 rated coöperating valve-member rotatably mounted in said body.

3. The combination of a drain-pipe having an upwardly extending inlet-terminal, a back-water valve in said pipe, a ring secured 80 to said pipe and provided with a valve-seat, a valve cage in said terminal, and a wedge and interlocking connection between said ring and said cage for removably securing the cage and ring together. 85

4. In a floor drain, the combination of a receiver-basin, having an open top, a strainer-top in said opening, and connections at either side below said top, a drain-pipe connected to receive drainage from said basin 90 and having a trap therein, shoulders on the receiver-basin above said inlet connections and the inlet terminal of the drain-pipe, a removable strainer-plate adapted to rest on said shoulders, the latter strainer having a 95 perforated portion above the inlet terminal of the drain pipe, and means at the inlet terminal of said pipe having a closed top and vertically extended openings in its side, leading to the passage in said drain-pipe for pre- 100 venting the escape of gas through the drain pipe when the water trap is inoperative.

GEORGE J. DEHN.
